(57) **CLAIM**

The ornamental design for an optical disk apparatus, as shown and described.

DESCRIPTION

FIG. 1 is a perspective view of a “optical disk apparatus” showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

As used herein, an optical disk apparatus includes players and/or recorders for DVDs (digital versatile disks) as well as other optical disk formats.
